POOL GAME BOARD

Roy V. De Voy, North Hollywood, Calif.

Application April 29, 1949, Serial No. 2,339

Term of patent 3½ years

(Cl. D34—3)

To all whom it may concern:

Be it known that I, Roy V. De Voy, a citizen of the United States of America and a resident of the city of North Hollywood, in the county of Los Angeles, and State of California, have invented a new, original, and ornamental Design for Pool Game Board, of which the following is a specification, reference being had to the accompanying drawings, forming a part thereof.

In the drawings:

The underside of the game board is plain.

I claim:

The ornamental design for a pool game board, substantially as shown and described.

ROY V. DE VOY.
